JOHN H. ROBBINS, OF INDIANAPOLIS, INDIANA, ASSIGNOR TO ALBERT D. ROMANS, OF INDIANAPOLIS, INDIANA.

SIDE-FILING MACHINE AND EQUALIZER FOR BAND AND OTHER SAWS OF LIKE CONSTRUCTION.

1,242,726.

Specification of Letters Patent.

Patented Oct. 9, 1917.

Application filed October 4, 1915. Serial No. 53,969.

To all whom it may concern:

Be it known that I, JOHN H. ROBBINS, a citizen of the United States of America, residing at Indianapolis, in the county of Marion and State of Indiana, have invented 5 a new and useful Side-Filing Machine and Equalizer for Band and other Saws of like construction.

My invention relates to improvements in 10 saw-sharpening and side dressing machines.

The invention has for its object to provide a device of the character described which may readily be attached to the saw blade without the necessity of removing the 15 latter from the mill wheels.

A further object is to provide a device which will sharpen and aline the teeth on both sides of the saw while the saw is in motion.

20 Other and further objects will be in part described and in part obvious as the description is proceeded with.

In the accompanying drawings:

Figure 1 is a perspective view of the invention;

Fig. 2 is a perspective view of the anvil and wheel detached;

Fig. 3 is a central vertical sectional view;

Fig. 4 is a sectional view on the line 4—4

30 Fig. 3 and

Fig. 5 is a sectional view taken on the line 5—5 Fig. 3.

Referring more particularly to the drawings in which similar reference numerals are 35 used to designate like parts throughout the several views, the numeral 1 designates a saw guide formed with a slot 2 through which a power driven or otherwise suitably actuated saw 3 is adapted to work. The 40 sharpening and dressing machine consists of a pair of spaced arms 4 preferably of angle iron and of U-shape in cross section, each arm being provided at its forward extremity with an integral leg 5. The other 45 end of the arms 4 have secured thereto a pair of supporting legs 6, a U-shaped leaf spring 7 being utilized for this purpose. This leaf spring also performs the added function of yieldingly maintaining the arms 50 4 in spaced parallel relation one to the other. The legs 5 and 6 are adapted to rest upon the saw guide 1 and thus support thereabove the arms 4 together with parts connected thereto.

Attached to the forward ends of the arms 55 4 is a pair of clamping plates 19 formed with inwardly extending flanges 8 for a purpose about to be described. The arms 4 are formed with similar flanges 9 which with the flanges 8 form jaws between which 60 a pair of files 10 are adapted to be clamped. In order that files of different widths may be accommodated the clamping plates 19 are mounted for longitudinal adjustment toward and away from the extremities of the 65 arms 4 as by bolts 11. It will also be noted that the files are vertically and angularly disposed so that their inner longitudinal edges converge toward the saw teeth 12 when the device is clamped upon a saw. 70

Means for steadyng the saw during the sharpening and side dressing operation is provided, said means in the preferred embodiment of the invention comprising a sliding bifurcated block 13 between the legs 75 14 of which is mounted a grooved wheel 15 adapted to receive the back edge of the saw. The block 13 is adapted to be adjusted longitudinally between the arms 4 by means of threaded spindle 16 and handle 17 thus 80 adapting the machine for use on saws of varying widths. Thumb screws 18 are provided for laterally centering the saw with respect to the opening between the files and to allow for varying thickness and width of 85 swage of the saw teeth.

In practice, after the saw has been filed and swaged the machine is placed over the saw from the back thereof, the files adjusted to the side of the saw teeth and the wheel 90 15 caused to engage the back of the saw. The sharpening and alining operation is effected by the passage of the saw teeth between the files, the attention of an attendant being unnecessary once the proper adjustments have been made. 95

From the foregoing it will be seen that I have invented a simple, economically constructed and efficient device for filing, equalizing and alining up the teeth of a saw while 100 the latter is running on the wheels of a mill.

Having thus described my invention,

What I claim is:

1. A saw sharpening and side dressing 105 implement comprising a pair of spaced U-shaped arms each arm being formed at its forward extremity with an integral leg, a

U-shaped spring connecting the other end of said arms together, a pair of legs secured to said spring, an antifriction saw engaging member slidably mounted between said arms, means for adjusting the position of said member longitudinally of said arms and means for securing a pair of files to the free ends of said arms.

2. A saw sharpening and side dressing implement comprising a pair of spaced arms, a resilient member connecting said arms at one end and normally forcing them

toward each other, means for securing a pair of files to the other end of said arms, a bifurcated block slidably mounted between said arms, a grooved wheel mounted in said bifurcated block, and manual means mounted in said resilient member for moving said block and wheel.

JOHN H. ROBBINS.
